ENVELOPE

Edward R. White, New Rochelle, N. Y.

Application December 21, 1945, Serial No. 636,302

9 Claims. (Cl. 229—82)

1

This invention relates to envelopes and more particularly to means securing the contents in the same.

The object of the invention is to utilize the material necessary for a blank form of an ordinary envelope, and provide therefrom the necessary parts to seal the envelope.

The invention consists in providing the usual enveloping member closed at all sides, excepting for the flap end, with a sheath at the flap end, this sheath having an entrance slot, a tongue being provided to enter the slot and be held by the sheath, the tongue bridging the open end of the envelope. The tongue is provided with means for securing the envelope against accidental opening, or the tongue may be made in two parts, one for detachable closing the open end of the envelope, and the other tongue for sealing the envelope. The tongue may be placed off center to the slot in the sheath to provide a friction hold.

The invention will be further described hereinafter, embodiments will be shown in the drawings, and the invention will be finally pointed out in the claims.

In the accompanying drawings,

Fig. 1 is a perspective view of the improved envelope, showing in full lines the tongue inserted, and in dotted lines the tongue when extracted;

Fig. 2 is a partial longitudinal section taken on line 2—2 of Fig. 1;

Fig. 3 is a diagrammatic drawing of Fig. 2;

Fig. 4 is a transverse end section taken on line 4—4 of Fig. 1;

Fig. 5 is a fragmentary enlarged view of the tongue in the sheath;

Fig. 6 is a plan of the blank for the envelope shown in Fig. 1;

Fig. 7 is a partial perspective view of a modified form of tongue;

Fig. 8 is a rear view of the structure of Fig. 7, in sealed position;

Fig. 9 is a front view of Fig. 8;

Fig. 10 is a section taken on line 10—10 of Fig. 8;

Fig. 11 is another modified form of the tongue;

Fig. 12 is still another modified form of the tongue, and

Fig. 13 is a modified form of the sheath flap.

Similar characters of reference indicate corresponding parts throughout the various views.

Referring to the drawings, the blank for the envelope shown in Figs. 1 to 4, is shown in Fig. 6. This blank has a front portion 10, a back portion 11, and a cooperating back portion 12, these back portions 11 and 12 extending laterally of the

2

front portion 10. The lower part of the front portion 10 is provided with a flap 13. The back portions 11 and 12 are provided with lanes 14 of adhesive. The upper part of the front portion 10 is provided with a flap 15, which is used to form a sheath with the inside of the front 10. At the junction of the front 10 and the sheath member 15, a curved slot 16 is cut as shown in Fig. 6, forming an extension or sheath flap 17 of the front portion 10. This sheath flap 17 may have the shape of the sheath flap 11a, shown in Fig. 13 viewed from the front of the envelope. The back portion 11 has an extension 20 integral therewith, and this is preferably provided with a sinuous shaped side 21. A tongue reinforcing member 18 is preferably provided with spots 22 of adhesive. The adhesive lane 14 extends along the marginal portion of the back portion 11, and over the tongue 20. The lane 14 extends also on to the extension as at 22a. Crease or bend lines are provided, namely 13a for the flap 13; 12a for the back portion 12; 11a for the other back portion 11; 15a for the sheath forming flap 15; and 20a for tongue re-inforcing member 18 enable the parts described to be folded in the desired envelope positions, in the manner well known.

The re-inforcing member 18 is folded along the line 20a and reinforces the lateral edge portion of the back portion 11, the adhesive holding the parts together. The flap 13 is folded along the line 13a; then the two back portions 11 and 12 are folded along the lines 11a and 12a and secured to the flap 13 by the adhesive in the lanes 14. Thereby the envelope pocket is formed. When so folded, the sheath forming member 15 is inserted into the envelope pocket as shown in Fig. 2, and the tongue 20 extends out of the pocket as shown in dotted lines in Fig. 1.

After the contents have been inserted into the envelope proper, the sheath forming flap 15 having been tucked in to form the sheath inside of the envelope, the tongue 20 is inserted into the slot 16. The tip of the tongue 20 strikes the extension 17, and is guided thereby in order to enter the sheath formed by the front portion 10 and by the inner flap 15. The base of the tongue 20 is disposed slightly off center or slightly displaced so as to take the position shown in dotted lines in Fig. 5. After the tongue 20 has been completely inserted it is released and then it springs into the position shown in full lines in Fig. 5. This facilitates the entrance of the tongue into the slot, and gives a good holding action. The tongue 20 has a curved part 21

which also acts as a camming lock preventing the tongue from coming out or being forced out by the contents of the envelope. If desired, the adhesive spot 22 on the rear of the tongue may be moistened, and then pressure will cause the tongue to adhere, and thereby seal the envelope. It will be noted that the tongue 22 bridges the open end of the envelope, as shown in Fig. 4.

In the modified form shown in Fig. 7, the tongue is formed of two loose parts 26 and 27, the tongue 26 being guided by the sheath flap 17 and entering the slot 16 as described, and the tongue 27 entering a slot 28 in the front wall 10, the tongue 27 being provided with a spot 29 of adhesive, to seal the envelope if desired. Both tongues 26 and 27 may be inserted into the slot 16 if desired, which enables the envelope to be openable. Figures 7 to 10 show the double tongue embodiment.

The tongue 30 in Fig. 11 may be provided with a notch 31, and this is engaged by the folded portion of the sheath flap 15, when the tongue is inserted. Or, the tongue 31 of Fig. 12 may be without curves or notch, and has even or straight sides, and may then be inserted into the sheath portion.

The tongues 30 and 31 of Figures 11 and 12 are given as examples. Either may be provided with sinuous curves, or made in two parts as described; or the tip may be made flat, as shown for instance in Fig. 7. Or, the tongue 26 or 27, or the tongue 28, may have its ends curved or pointed as shown in Figs. 11 and 12.

The important feature is the provision of the sheath by bending over a flap of one end of the front portion 10, in the embodiments shown, and providing an entrance slot for the sheath, and providing a tongue on the opposed rear or back portion, so that the tongue bridges the open end of the envelope and enters into the slot and is frictionally engaged by the sheath portion, whereby a simple and efficient closure of an envelope is provided. The tongue is made of material which is otherwise wasted, when the usual closing flap 15 is cut from the blank. The envelope may be used in the mails without the contents emerging, as the tongue in the sheath provides a secure closing member.

When the double tongue as shown in Fig. 7 is preferred, the blank of Fig. 6 is provided with a slit for the length of the tongue along the score line 20a.

The invention has been described in connection with a single seam envelope, but it is applicable to a double side seam envelope, in which case the tongue is secured preferably by an adhesive to the back portion, so as to enter the slot in the sheath, which slot may be straight, instead of curved, if so desired.

The word "envelope" includes articles commonly known in the trade as bags, for shipment of merchandise, which bags are made by the identical envelope making machinery.

I have described several forms of my invention, but obviously various changes may be made in the details disclosed without departing from the spirit of the invention as set out in the following claims.

I claim:

1. In a single seam envelope consisting of a single front, two side flaps on the sides of said front permanently joined at their free ends to form the back, a bottom flap folded over the two side flaps forming the back and permanently joined thereto, and a flap extending from the front beyond the back and having a fold line

adapted to form a closing flap for the envelope, the combination of a sheath formed by the closing flap placed between the front and back with a slot on the fold line of the closing flap, a tongue flap on one of the side flaps substantially of a length equal to the length of the closing flap and of a width substantially equal to the width of the slot, whereby the entrance of the tongue flap into said slot, and the bridging of the space between the front and the closing flap and the engaging of the sheath, the front and back are held closed without the need of other fastening means.

2. The structure of claim 1, in which said tongue has a width at its base substantially equal to the length of the slot and has a curved portion at one side of the tongue.

3. The structure of claim 1, in which said tongue has a curved portion of sinuous shape and a narrower part at its base of substantially the length of the slot.

4. The structure of claim 1, in which said tongue has a curved portion of sinuous shape, the curved edge of the tongue being out of alignment with an edge of said slot, and the part of the tongue at its base registering with one end of the slot.

5. The structure of claim 1, in which said tongue has a curved portion of sinuous shape, the curved edge of the tongue being out of alignment with an edge of said slot, and a spot of adhesive on one side of said tongue.

6. The structure of claim 1, in which said tongue has a curved portion of sinuous shape, the curved edge of the tongue being out of alignment with an edge of said slot, and a spot of adhesive on one side of said tongue, said tongue being formed of superposed parts, one of which enters said slot of said sheath, and said first body portion having a slot near the edge slot engaged by the other tongue.

7. The structure of claim 1, in which the front has an extension along the slot extending beyond the edge of the front to act as a guide for the entrance of the tongue into said slot.

8. As an article of manufacture, a blank for a single seam envelope, comprising a front portion, surrounded by side flap portions and a bottom flap portion, scored to be bent to form an envelope with adhesive to join said flap portions to form a single seam envelope with three ends closed and one end open, another flap portion adapted to be bent inside the envelope forming a crease and a sheath along one edge of the front portion at the open end, and having a slot in the crease, one of the envelope forming side flap portions having an extension parallel with the sheath forming flap portion, to utilize the material of one of the side flaps ordinarily waste, to form a tongue of substantially the same length of the sheath flap and of a width substantially the same as the slot.

9. In an envelope consisting of a single front, two side flaps on the sides of said front, a bottom flap folded over the two side flaps and permanently joined thereto to form the back, and a flap extending from the front beyond the back and having a fold line adapted to form a closing flap for the envelope, the combination of a sheath formed by the closing flap placed between the front and back with a slot on the fold line of the closing flap, a tongue flap on the back flaps substantially of a length equal to the length of the closing flap and of a width substantially equal to the width of the slot, whereby the entrance of the tongue flap into said slot, and the bridg-

ing of the space between the front and the closing flap and the engaging of the sheath, the front and back are held closed without the need of other fastening means.
